UNITED STATES PATENT OFFICE.

HARRY F. MYERS, OF LANCASTER, AND EDGAR E. SNYDER, OF COLUMBIA, PENNSYLVANIA.

PREHEATER FOR STOVES.

1,202,089.

Specification of Letters Patent. Patented Oct. 24, 1916.

Application filed January 28, 1916. Serial No. 74,927.

To all whom it may concern:

Be it known that we, HARRY F. MYERS and EDGAR E. SNYDER, citizens of the United States, residing, respectively, at Lancaster 5 and Columbia, in the county of Lancaster and State of Pennsylvania, have invented new and useful Improvements in Preheaters for Stoves, of which the following is a specification.

10 The present invention relates to preheaters for stoves, and is intended to bring about a more perfect combustion and consumption of the fuel gases by delivering to the firebox a volume of heated air which will not 15 only promote fuel combustion but will bring about a burning of the fuel gases thrown off by such fuel during burning.

It contemplates as its preferred embodiment a stove lid of not unusual form and 20 dimensions, which is provided with adjuncts which insure the preheating and delivery to the fire-box of a sufficient volume of air to bring about the results aimed at, provision being made for regulating and controlling the delivery of preheated air to 25 meet the necessities of the case.

Broadly considered, preheating lids for delivering air to the fuel box are old and we do not claim to be the first to have conceived of this broad idea and embodied it 30 in a preheating lid, but the present device is an improvement on certain devices now known to us, the construction which we have developed being simple and cheap of 35 manufacture and at the same time giving a highly efficient device.

In the drawings herewith we have shown one embodiment of our invention, and in said drawings,—Figure 1 is a plan view of 40 a stove lid embodying our invention, certain parts being shown in dotted lines. Fig. 2 is a sectional view of the lid shown in Fig. 1, the scale of Fig. 2 being somewhat greater than the scale to which Fig. 1 is drawn, 45 for clearness of illustration. Fig. 3 is a plan view of the heating chamber which is attached to the lid proper in order to show the interior construction of that chamber.

50 Referring to the drawings, like numbers indicating like parts in the several views, 10 denotes the lid proper having the lifter aperture 11, and, as herein shown, provided centrally with an intake opening 12. This intake opening is surrounded by a wall 13 55 within which is mounted a regulating and

controlling slide 14 pinned in place by a pin 15 passing through a slot in the slide 14. The said slide 14 is designed to control and regulate the intake aperture 12, the various positions of the slide 14 being indicated in 60 Fig. 1 in full and dotted lines. The said wall 13, in conjunction with lugs 16 symmetrically disposed on the lid 10, serves as a support for such kitchen utensil as may be used, holding such utensil in elevated position and also forms a guide for the regulating plate 14. In order that there may be free flow of air to the intake aperture 12, I 65 preferably cut the wall 13 by means of channels 17, 18 and 19, as shown in Fig. 1, and 70 these channels are so disposed relative to the intake aperture as to serve as directing means to indicate the several positions of the slide 14. It will be observed (Fig. 2) that the slide 14 is disposed in a plane below the top of the wall 13 and below the delivery mouths of the channels 17, 18 and 19, so that there will be no interference with the delivery of the air by these channels to the aperture 12. The channel 17 is so 75 80 placed as that, when the slide is fully open, the aperture 12 will be completely uncovered and a full draft of air to be preheated will pass through the intake to the preheating chamber, presently to be described, and I 85 preferably provide the slide 14 with an arrow or other indicator, 20, which, when it registers with the channel 17 and the legend on the top of the lid adjacent such channel, 90 will give the full volume of air. The channel 18, which is slightly in advance of the channel 17, and opposite which is another legend, will indicate the point to which the slide 14 is to be adjusted to cut down the volume of air flowing through the aperture 95 12, and a pointer or other indicating mark 21 will preferably be provided so as to show when the slide has been brought into proper position to limit the flow of air. The channel 19 marks the limit of closing movement 100 of the slide 14 so that, when the arrow 20 points to this channel, the flow of air through the aperture 12 will be entirely cut off, and this furnishes a convenient and direct means of indicating the proper position 105 of the plate.

Secured to the lid 10 is a depending chamber 22 preferably fastened by screws 23 so that it may be readily detached for cleaning or repairs, the said depending chamber 22 110

having a tight joint where it contacts with the lid 10, such joint being effected preferably by a rib 24 and a packing 25, preferably of asbestos or other heat resisting material, as shown in Fig. 2.

In order to prevent ingress of air except through the central intake aperture 12, we provide a boxing 26 to cover the lifter opening 11, as shown in Figs. 2 and 3, so that 10 the air delivered to the heating chamber 22 must pass through the intake aperture 12 and its flow can, therefore, be controlled by the slide 14. Beneath the intake aperture 12 and preferably formed integrally with the 15 chamber 22, we provide an intake chamber 27, shown in the present illustration as rectangular in form, this centrally disposed intake chamber 27 having distributing outlets 28, four being shown in the present instance, which outlets 28 are preferably arranged symmetrically, so that the air delivered to this intake chamber through the 20 intake aperture 12 will be distributed in regular symmetrically disposed streams to 25 the interior of the casing 22, and a regular and uniform heating of these several streams of air will take place, for by this construction they are distributed from the intake chamber 27 evenly throughout the interior 30 of the depending chamber 22.

As shown in Figs. 2 and 3, the chamber 22 has its bottom crowned so as to give a heating chamber the under surface of which is of increased area, and the vertical dimension 35 of which enlarges outwardly from the center, so that the air coming through the intake aperture 12 in relatively cool condition will, as it expands under the heat of the chamber, flow outwardly toward the periphery thereof into the increased or enlarged area, and its point of entrance being at the apex of this crowned bottom its initial heating will be comparatively rapid.

At one side of the chamber 22, and preferably in the side wall thereof, we provide a 45 series of delivery apertures 29 through which the heated air will be ejected by reason of its expansion to the fuel-box, the lid 10 being so placed that these apertures 29 will be directed toward the fuel box, and in order that the proper position of the lid and delivery apertures 29 may be always determined, we provide the lid 10 with an 50 indicating mark, as the arrow 30, which, when it points in the direction of the fuel-box, will insure the proper position of the apertures 29 and the delivery therethrough of the heated air to the fuel-box.

The device may, of course, be used in substitution of an ordinary lid at any point on the stove top where it is found advantageous, but preferably this preheating lid will be located to one side of the fire-box. It is found advantageous to place it adjacent the 65 stove pipe or flue, although naturally its

position on the stove top is a matter which can be varied as the needs of the user may require.

We have found that this construction comprising the main heating chamber with the 70 crowned or upwardly bulging bottom and the centrally-disposed intake chamber which receives the outside air from the intake aperture 12, enables us to do away with any complicated or extended channels or 75 passages to secure the heating of the air, this breaking up and distributing in symmetrically-disposed streams of the air to be heated insuring its quick and complete heating and expansion and its delivery in proper condition to the outlets 29; the crowning of the 80 bottom of the heating chamber insuring a relatively quick initial heating and rapid expansion into the open chamber. Furthermore, the system of regulation and control of the 85 air by means of the slide for the intake aperture 12 and its directing indicia insures an 90 easy and intelligent regulation of the device to meet the several conditions under which it is used.

The construction is simple and comprises but the two main castings and the regulating slide, all of which may be inexpensively produced and assembled, and the construction of which is such that impairment 95 or destruction from overheating is practically eliminated.

We claim:—

1. An air heating lid for stoves comprising a top having a centrally-disposed air 100 intake aperture, a slide controlling said aperture, a heating chamber having an open interior depending from said top and provided with delivery apertures, and a centrally-disposed air-receiving and distributing chamber within said heating chamber to which said intake aperture delivers, said distributing chamber being closed at its top and bottom and having apertures in its side walls.

2. An air heating lid for stoves comprising a top having an air intake aperture, a wall surrounding said aperture and having a series of intake channels therein, a slide within and guided by said wall to control 115 said aperture, said slide lying in a plane below the top of the wall and the intake channels therein and adapted to register with each of said channels, and a heating chamber having an open interior depending 120 from said top and provided with delivery apertures.

3. An air heating lid for stoves comprising a top having an air intake aperture, a wall surrounding said aperture and provided with intake channels, a slide within and guided by said wall to control said aperture, said slide lying in a plane below the top of the wall and the intake channels 125 therein and adapted to register with said 130

channels, indicia adjacent each channel indicative of various positions of said slide, and a heating chamber having an open interior depending from said top and provided 5 with delivery apertures.

4. An air heating lid for stoves comprising a top having an air intake aperture, a rectangular wall surrounding said aperture and having air intake channels adjacent said 10 aperture, a slide disposed within and guided by said rectangular wall and provided with positioning indicia, indicia on said top adjacent the intake channels and said wall to indicate the several positions of said slide, 15 and a heating chamber having an open interior depending from said top and provided with delivery apertures.

5. An air heating lid for stoves comprising a top having a centrally-disposed air intake aperture, means for controlling said aperture, a heating chamber depending from 20 said top and having a centrally crowned or upwardly bulging bottom, and an integrally-formed receiving and distributing

chamber rising from the apex of said 25 crowned bottom, said distributing chamber being closed at its top and bottom and provided with apertures in its side walls through which the air from the intake aperture is distributed.

6. An air heating lid for stoves comprising a top having an air intake aperture, a wall surrounding said aperture and having a series of intake channels therein, a slide 30 to control said aperture, indicia on said lid 35 adjacent said wall to indicate various positions of said slide, and a heating chamber having an open interior depending from said top and provided with delivery apertures.

In testimony whereof we have hereunto set our hands in presence of two subscribing witnesses.
